UNITED STATES PATENT OFFICE.

PETER K. DEDERICK, OF ALBANY, NEW YORK.

BALING-PRESS.

SPECIFICATION forming part of Letters Patent No. 269,566, dated December 26, 1882.

Application filed May 14, 1880. (No model.)

To all whom it may concern:

Be it known that I, PETER K. DEDERICK, of Albany, in the county of Albany and State of New York, have invented certain new and useful Improvements in Baling-Presses; and I do hereby declare the following to be a full, clear, and exact description of the same, reference being had to the accompanying drawings, forming a part of this specification, in 10 which—

Figure 1 is a longitudinal sectional view of a press embodying my invention. Fig. 2 is a front elevation of one of the movable partitions. Fig. 3 is a view of the mechanism for shipping 15 the feeder. Fig. 4 represents one of the movable sections composing the side of the bale-chamber. Figs. 5, 6, and 7 are respectively sectional, cross-sectional, end, and longitudinal sectional views of the bale-chamber provided with friction-lining, said lining in Fig. 5 being represented as stationary, and in Figs. 6 and 7 as movable.

Similar letters of reference in the several figures denote the same parts.

This invention relates to improvements in 25 that class of baling-presses covered by Letters Patent granted me October 29, 1872, Nos. 132,566 and 132,639, and by various patents granted to me since that date.

It consists in the several improvements which 30 will be hereinafter described and claimed.

Referring to the drawings, A, Fig. 1, represents the press-box of the press; B, the bale-chamber; C, the reciprocating traverser; E, 35 the hopper; F, the pitman, and G the crank-wheel by which motion is imparted to the pitman to reciprocate the traverser back and forth.

H represents the feeder, mounted upon the 40 rock-lever H' in the usual manner, constructed of a size to fill the feed-orifice when depressed to its lowest position, and K is a spring secured to the inner lining of one wall of the feed-hopper and operating, when the feeder is depressed, to spring out and engage with a shoulder, N, 45 on the feeder and lock the latter in position. Connected to the lower end of this spring is a rod, m, which passes through the wall of the hopper and is articulated to the lower end of the lever L, pivoted at l, outside of the hopper, 50 as shown.

Mounted upon the vertical staff N, secured to the traverser, is a stud or arm, M, which op-

erates, when the traverser is near the limit of its forward movement, to strike the upper end of the lever L, and thus retract the spring K, 55 release the feeder H, and allow said feeder to rise by the action of the counterbalancing-weight O on the outer end of the rock-lever H' and permit the hopper to be filled with loose material. By causing the feeder H to descend 60 and fill the feed-opening and remain in that position while the traverser is moving forward the traverser is enabled to force the charge of material into the bale-chamber with greater facility than if the feed-opening were not so 65 closed and portions of the material were allowed to project up into the feed-opening, as ordinarily.

Instead of the described devices for holding the feeder locked, any other suitable devices 70 that will perform the function may be employed.

The condenser P is caused to move back and forth in the feed-hopper by means of a connecting-bar, N², secured to the upper end of the staff N of the traverser in the well-known 75 manner; but inasmuch as said condenser must be moving slowly forward toward the feed-opening while the feeder H is descending, I preferably provide the condenser with a concave face, so as to prevent by any possibility 80 a binding of the parts. The rock-lever H' passes through a slide-bar, R, near its outer end, and the latter plays up and down through guides R', as shown. As the crank of the 85 crank-wheel G moves up the end of the pitman F strikes the lower end of the bar R and raises the latter, and with it the outer end of the rock-lever H', thereby causing the descent of the feeder. Ordinarily each revolution of the crank-wheel will cause the feeder to descend 90 once; but in order that the rod R may be swung outward, so that the pitman will not strike it when for any reason that is deemed necessary, I provide a rod, W, guided at X, and having at its outer end a band, U, which 95 loosely encircles the rod R, and connected at its other end, at Z, to a lever, Y, pivoted near the hopper, as shown in Fig. 1. When the lever Y is moved in one direction and engaged with a locking-notch, l, the rod R will be held in the path of the end of the pitman F; but when said lever is moved in the opposite direction and engaged with the other notch 1 the bar R will be swung out of the path of the

end of the pitman, as shown in the dotted lines, Fig. 1. In order to give the bar R the requisite lateral play, the cross-timber S is slotted, as shown. The sides of the press-box at the 5 end of the slots in the bale-chamber are provided with projections 3, and the traverser has recesses D to engage with the projections 3, as shown. The partition-followers for separating the bales are each provided with recesses 4, as 10 shown in Fig. 2, to engage with the projections 3 and allow the partitions to pass the press-box, and also to hold the said partitions in an upright position. I construct the ribs or sides of the press between the tie-slots, Fig. 4, so as 15 to hinge them next the press-box by a pin passing through the hole 6 and through timbers and projections on the sides of the press-box near the point 3. The advantage of thus hinging the sides is of more importance in an 20 iron press than in a wooden press, for in adjusting to secure friction the wood will spring, while iron would break if not hinged. I line the inside of said chamber on two or all sides with movable endless belts of leather, rubber, 25 cloth, or other suitable material. Said endless belts pass along the inner surface of the chamber, out at the discharging end of the bale-chamber, and along between flanges on the outside of the chamber to and through the openings 16, 30 Fig. 7, at the junction of the press-box and bale-chamber, into the inside of the bale-chamber. When the belting is used on the sides several belts are used, in order to leave openings for the tying-slots, each belt being kept in place 35 by flanges, as shown in Figs. 4, 5, and 6. The object of this lining is to produce increased friction, and is essential in pressing cotton very hard. Instead of a movable-belt lining, the leather or other material may be fastened 40 in any suitable manner to the inner surfaces of the bale-chamber, as shown in Fig. 5, or both a fixed friction-lining and a movable friction-lining might be used, thus greatly increasing the friction.

45 A modification of my invention is shown in

Fig. 1 at 7, 8, and 9, where the bale-chamber is provided with a series of corrugations or shoulders on two or all sides. Said corrugations may be cut into the sides of the chamber, as at 9, Fig. 1, or may be formed by inserting 50 pieces or sections, as at 7 and 8, Fig. 1. The bale-chamber is provided with an adjustable head, and is provided with two hooks, one at the top and bottom, or one on each side, as shown at 10, Fig. 1, and hinged at 11, each 55 hook being of sufficient length and width to cover the end of the chamber, and when in use being retained in position by a yoke hinged to one hook at 12, Fig. 1, and yoking over the other hook, as shown in said figure. 60

Having thus fully described my invention, I claim—

1. The combination, with the press-box, of the feeder and the locking devices for automatically locking the feeder when depressed, 65 substantially as described.

2. The combination, with the press-box, of the feeder, the devices for automatically locking the feeder when depressed, and the projection on the traverser for unlocking the locking devices and releasing the feeder, substantially as described. 70

3. The combination of the rod W with the slide-bar R, for the purpose set forth.

4. The clamps or hooks 10 and yoke 12, in 75 combination with the chamber of a baling-press, for the purpose set forth.

5. The sides of the bale-chamber between the tie-slots hinged to the press-box, as set forth. 80

6. In a baling-press in which the material is forced in sections within a bale-chamber and built up into a bale therein by a reciprocating traverser, the said bale-chamber, having its lining composed in whole or in part of movable 85 belts, substantially as described.

P. K. DEDERICK.
